UNITED STATES PATENT OFFICE.

ADRIEN GODIN, OF PARIS, FRANCE.

ELEVATOR, CONVEYER, AND CRANE.

1,396,193.

Specification of Letters Patent.

Patented Nov. 8, 1921.

Application filed April 30, 1919. Serial No. 293,758.

To all whom it may concern:

Be it known that I, ADRIEN GODIN, citizen of the Republic of France, residing at 10 Rue de la Motte Piquet, Paris, in the 5 Republic of France, have invented new and useful Improvements in Elevators, Conveyers, and Cranes, (for which I have filed applications in France as follows: Sept. 14, 1917, Ser. No. 94,461, Feb. 20, 1918, Ser. No. 10,710, June 24, 1918, Ser. No. 10,997,) of 10 which the following is a specification.

In hoisting apparatus of present construction with either grabbing or tipping buckets used for handling heavy material such as 15 ores, coal and the like the duration of each operation is greatly increased by the horizontal circular or rectilinear displacements of the bucket. Generally, the duration of 20 a complete handling operation of a bucket is about double that of the mere hoisting operation.

The object of this invention is to dispense with all horizontal motion of the bucket which thus remains in the same vertical 25 line and hoists but does not convey horizontally. From such economy of motion and time there results a considerable increase in the efficiency of the bucket.

This invention consists in the combination 30 with a hoisting apparatus embodying a vertically movable bucket, or two balanced buckets movable in opposite directions, of a conveyer located clear from the vertical path of the buckets and a receiving device 35 adapted to receive the material dropping from the bucket and discharge the same onto the conveyer, said conveyer being so supported that it may be displaced horizontally in all directions. This last feature is especially important since it permits 40 for instance to bring the conveyer to the most convenient position for operation and remove or displace the same when the operation is completed so as to clear the boat 45 if the conveyer was supported on a boat or entirely clear the water if the conveyer is supported on a gauntree crane or similar apparatus.

Other features of the invention will be 50 apparent from the following description.

In the accompanying drawings shown by way of example, Figure 1 is a perspective view of the whole apparatus with the screen raised by means of chains and of a frame

raised by the bucket. Fig. 2 is an elevation 55 of the whole showing a different mode of raising the screen. Figs. 3 and 4 show an automatic device for retaining the screen, provided upon the edge of the hopper. Fig. 5 is a modification wherein the screen is done 60 away with but where the hopper rolls so as to be able to come under the bucket at the time when it is opened. Fig. 6 is an elevation of the apparatus suspended to the portal of a crane in a tidal harbor instead 65 of being placed on the ship.

In Fig. 1 the bucket or grab *a* which may be either of the automatic or tipping type is suspended from the hoisting chain or cables of an ordinary crane. Under the 70 same, over the hold, is placed the improved auxiliary apparatus according to this invention which comprises: the disappearing screen 1 turning about the horizontal axis 2 and its counterweight 3, the hopper 4 provided 75 with a spout or flap 5 capable of moving about a horizontal axis 6; this spout can be either fixed or freed by means of the releasing gear 7. The apparatus comprises also a continuous conveyer 8 which passes under 80 the hopper and is used to carry away its contents.

The whole apparatus is fixed upon two beams 9 placed at suitable intervals and connected together by the tie bars 10. 85

These beams rest upon the ledges 11 of the hatchway by means of clamps 12 provided with two series of rollers allowing the apparatus to be moved along in two directions at right angles to each other above 90 the hold.

The screen is propped up by the trestle 13 carried by the beams 9 upon which it is fixed by means of bolts or clamps so as to be able to have its position regulated. 95

When the apparatus is in position for work, the bucket is in the axis of the opening between the beams; the screen may by turning upon its joint come to bear upon the hopper flap 5 or disappear in a vertical 100 position. As the bucket ascends, it raises the screen by engaging upwardly into a frame 14 connected to the screen by small chains 15.

At this time the engineer opens the bucket 105 whose contents fall upon the screen inclined at such a pitch as to allow the material to run down straight into the hopper,

Immediately after this, the retaining gear 7 of the flap is opened by the engineer with the aid of a pull handle or by an assistant at hand, the flap 5 yielding under the weight 5 of the screen drops down and allows the screen to fall and assume a vertical position in consequence of its weight not being properly balanced by the counterweight. In this downward motion the screen is held by 10 the chains 15; as the bucket descends the screen assumes its vertical position 1^a. The frame 14 which first followed the bucket is soon held by the chains 15 positioned at 15^a and fixed to the screen and it parts with 15 the said bucket in position 14^a, the bucket descending now alone to the bottom of the hold.

During the ascent all these movements take place in a reverse sense the bucket first 20 enters the frame 14, carries it along and raises the screen 1 until it meets the flap 5 which is first raised and then lowered while being automatically caught by the restraining gear. The engineer then has the bucket 25 opened while being lowered; at the same time the screen 1 suspended therefrom comes to bear upon the flap 5 during the discharge of the material from the bucket.

Fig. 2 is a side elevation of the apparatus 30 showing by way of example one of the various devices which may be used to automatically raise the screen.

Said device comprises cables or chains 17 fixed to the screen base and wound upon a 35 pulley 18 carried by the hopper, such pulley being actuated by a chain 19 transmitting the motion from the pulley 20 capable of being disconnected and mounted upon the axis of the front drum of the conveyer.

40 Figs. 3 and 4 show in elevation and in plan view one of the automatic retaining gears which may be utilized to fix the hopper flap 5.

In all cases this flap is hinged at 6. Fixed 45 at the flap ends are levers 24 provided with counterweights 25. When the screen assumes its working position under the bucket, it meets on its way up the flap 5 and causes it to turn until it escapes, the counterweights 50 25 which have been moved toward the bucket come back to a vertical position and bring the flap along into its waiting position. When the screen comes to bear on the flap it is stopped by the levers 24 owing to the 55 stop pieces 26 against which said levers abut.

After the bucket has been emptied, the screen is freed by acting on the push pieces 27; the stop pieces 26 are then freed by the 60 levers 24 which, under the action of the weight of the screen, assume a horizontal position corresponding to that in which the flap allows the screen to drop. As soon as the screen is gone, the counterweights 25 65 bring back the flap to its waiting position.

Springs 28 hold the push pieces 27 in contact with the levers 24. The stop pieces 26 have inclined surfaces allowing the levers 24 to pass over them at the time the counterweights return to their vertical positions. 70

A modification of this arrangement is shown in Fig. 5, wherein the screen is omitted, but the hopper 4 instead of being fixed to the conveyer or the beams can roll upon the beams 9 and come, as soon as the bucket is up, just below the same so as to receive its contents. When empty, the bucket comes down again while the hopper returns to its place over the conveyer where it lets down the material received by it at the same time as it clears 80 the way for the bucket which starts to fetch another load.

The displacement of the hopper at the right moment may be carried out—as for the screen—by the action of the bucket with the aid of a frame 29 and small cables or chains 30 passing over idle pulleys 31 and fixed to an arm 32 secured to the hopper. When in its loading position, the hopper is stopped by a retaining gear 33. As soon as the 90 bucket is empty, this gear is operated, close by or from a distance, to free the hopper which, under the action of springs, of gravity (the hopper rolling upon a sloping way) or of a special motor, is returned to its original position above the conveyer. In case of cable or chain motion, the bucket, as it descends, releases these bonds to allow the hopper to draw back, the frame follows the bucket and rests upon the beams 9. 100

When ascending, a reverse operation takes place, the length of chains and cables being calculated so that the bucket may open as near as possible to the hopper which should first have reached the retaining gear 33. 105

On account of the too great changes occurring in the water level of tidal seas, the apparatus cannot generally be placed on board ship. Fig. 6 shows the arrangement used in such cases. The beam 35 containing the 110 conveyer band is suspended from the portal or gauntlet of a crane or placed upon supports 36 the height of which may be suitably regulated; this beam is extended toward the ship by means of two arms 37 spread apart 115 and carrying the hopper and the screen trestle; on the other side, the beam reaches the wharf tracks whereon travel the cars requiring to be filled directly. To facilitate the drawing in of the part which projects 120 over the water, the beam may roll upon its supports in a sense perpendicular to the wharf. By means of cables or chains 38, handled by a hand winch or mechanically, the height of the apparatus above the wharf 125 may be altered so as to restore the normal height above the railway track if need be. The conveyer can deliver the material at any suitable point of its length onto intermediate tracks. 130

Having now described my invention what I claim as new and desire to secure by Letters Patent is:

1. The combination with a hoisting apparatus embodying a vertically movable bucket and means for operating said bucket, of a conveyer located clear from the vertical path of travel of the bucket, means for supporting said conveyer so that it may be shifted horizontally in all directions, for instance for the purpose of clearing a water way, and a receiving device adapted to either receive the material dropping from the bucket and discharge the same onto the conveyer or clear the vertical path of the bucket when the latter has discharged its contents.
2. The combination with a hoisting apparatus embodying a vertically movable bucket and means for operating said bucket of a conveyer located clear from the vertical path of travel of the bucket, means for supporting said conveyer so that it may be shifted horizontally in all directions, for instance for the purpose of clearing a water way, and vertically, for instance for the purpose of
- reducing to a minimum the vertical stroke of the hoisting bucket, and a receiving device adapted to either receive the material dropping from the bucket and discharge the same onto the conveyer or clear the vertical path of the bucket when the latter has discharged its contents.
3. The combination with a hoisting apparatus embodying a vertically movable bucket and means for operating said bucket, of a conveyer located clear from the vertical path of travel of said bucket, means for supporting said conveyer so that it may be shifted horizontally in all directions for instance for the purpose of clearing a water way, a pivoted, balanced and inclined screen adapted to either receive the material dropping from the bucket, or the vertical path of travel of the bucket and a receptacle adapted to receive the material from the screen and discharge the same onto the conveyer.

In testimony whereof I have signed my name to this specification.

ADRIEN GODIN.
